Primary Examiner — Marie D. Fast Horse*(74) Attorney, Agent, or Firm* — John K. Park; Park Law Firm(57) **CLAIM**

The ornamental design for a kiosk, as shown and described.

DESCRIPTION

FIG. 1 is a perspective view of a kiosk showing my new design;

FIG. 2 is a front view thereof;

FIG. 3 is a rear view thereof;

FIG. 4 is a left side view thereof;

FIG. 5 is a right plan view thereof;

FIG. 6 is a top plan view thereof; and,

FIG. 7 is a bottom plan view thereof.

The broken lines in the drawings depict portions of the kiosk that form no part of the claimed design.
